UNITED STATES PATENT OFFICE.

CARL A. WENDELL, OF JOLIET, ILLINOIS.

DRIER.

1,187,584.

Specification of Letters Patent. Patented June 20, 1916.

Application filed June 12, 1915. Serial No. 33,793.

To all whom it may concern:

Be it known that I, CARL A. WENDELL, a citizen of the United States, residing at Joliet, in the county of Will and State of Illinois, have invented a certain new and useful Improvement in Driers, of which the following is a specification.

My invention relates to a machine for drying materials and it is illustrated in a particular form of apparatus adapted for drying coal.

The drawings are more or less diagrammatic but sufficient to enable a skilled workman to construct therefrom a working machine.

In drying coal by centrifugal machines a considerable part of the problem is removing the dry coal from the machine after the water has been discharged by centrifugal force through a retaining screen.

My invention relates to means for moving the material to be dried continuously during the drying process along and over the screen to the surface.

My invention in the form in which I have designed it for use in connection with the drying of coal may employ discharge chutes depressed from and at an angle to the surface of the screen and scrapers which pass over the surface of such screen, and in the best form of my invention I use both of these features associated with a dish-shaped screen. In such an apparatus as that illustrated, the material is carried over the screening surface during the water expelling operation by centrifugal force and is discharged over the edge of the dish-shaped screen or through the inclined chutes and the screens are kept clean and the motion of the material facilitated by the scrapers, but of course not all of these peculiarities are modes of action or in every case essential. Indeed in certain kinds of materials while such a dish-shaped screen might operate for a certain length of time and to a certain degree, it is necessary nevertheless to scrape the material in order to keep the screen clean and to get proper action.

Figure 1 is a vertical section; Fig. 2 a horizontal section; Fig. 3 a cross section on the line 3—3 of Fig. 1.

Like parts are indicated by the same letter in all the figures.

A, A are frame and supporting pieces upon which are suitably mounted the bearings A¹, A², A³ and A⁴. The bearings A²

and A³ support the shaft A⁵, on one end of which is the driving pulley A⁶ and the gear wheel A⁷ and on the other end the beveled gear A⁸. The bearings A¹ and A⁴ support the shaft A⁹, on one end of which is the gear A¹⁰ slightly larger than and meshing with the gear A⁷ and on the other end is a beveled gear A¹¹.

B is a vertical shaft supported in the bearings B¹ and B² suitably supported on the lower part of the frame. This shaft carries the beveled gear B³ meshing with the beveled gear A⁸ and the hopper bottom B⁴ which carries the upwardly projecting dish-shaped screen B⁵ which is provided with an upper strengthening and material guide annulus B⁶. This annulus is cut away at B⁷, B⁷ to furnish an outlet for the discharge chute B⁸ whose bottom and sides may or may not be of screen material and which opens above through the cut-away portion of the annulus B⁶. I have shown two of these discharge chutes and their accompanying parts.

Mounted on the shaft B is a tight sleeve C carrying two spouts C¹, C¹. These spouts terminate above in the sleeve C² which surrounds the large feeding tube C³ into which the material is fed through the frame by the fixed chute C⁴.

D, D are spider arms on which the cylinder C³ is mounted and the spider is completed by the ring D¹. At the outer end of each of these arms is mounted a scraper D² by means of the connecting braces D³. Each scraper has preferably a brush edge D⁴ and a lower plow-like projection D⁵. The spider arms D together with the scrapers are mounted on the hollow shaft D⁶ supported on the sleeve C surrounding the shaft B and carrying the beveled gear D⁷ which is driven by the gear A¹¹. These parts are so associated and constructed that the screen with its discharge chutes and annulus and the supply chutes are rotated constantly in the same direction by the inner shaft at, for example, 400 revolutions per minute, while at the same time the spider scrapers and feed cylinder rotate with the hollow shaft at a slightly slower speed, say at 399 revolutions per minute. The feed chutes C¹, C¹ are positioned as indicated so that since they discharge tangentially they tend to deposit their material on the lower part of the screen slightly beyond the discharge chute in the direction of rotation.

E is a dish-shaped stationary water box with waste outlet E¹ and water trap rim E². This latter coöperates with the rim E³ on the screen, and the two together prevent the water from rising and overflowing into the coal box. Other desired means for drawing off the water could be employed.

F is a stationary material hopper with a return top F¹ to prevent the escape of the material which is discharged by centrifugal force from the screen and the discharge chutes upwardly and outwardly toward the rim and across the annulus. The dry material passes downwardly over the annulus into the coal box and may be allowed to escape at F¹ onto the conveyer belt F² which removes it to any desired position.

It will be understood, of course, that I do not wish to be limited to the particular size, shape, proportion and arrangement of the several parts here illustrated and that some of the features of my invention illustrated and described may be dispensed with without abandoning others. Many such changes are possible without departing from the spirit of my invention.

The use and operation of my invention are as follows: Assuming that the parts are arranged substantially as illustrated and set in motion, the material to be dried, as for example, coal, may be introduced through the supply chute C⁴ in the feed cylinder C⁵, whence it will pass down through the feed chutes C⁶, C⁷ and fall into the lower part of the dish-shaped screen just behind the chutes in the direction of the motion of the parts. Since the scrapers move a little slower than the chutes and the screen, though all move in the same direction, they will have an apparent motion in a direction opposite to that of the general motion of the parts, and thus the scrapers will tend to move the material along the screen surface toward the next chute. During this process the water will be expelled by centrifugal force and the material will tend to climb up the edge of the dish-shaped screen and pass outwardly over the annulus into the material box. Whatever does not so escape and whatever accumulation of material there may be upon the surface of the screen which for any reason does not move upwardly will be carried along by the scrapers until it reaches the discharge chute whereupon, the angle of inclination being greater and the material being discharged in such chute in a dried condition and the surface of the bottom of said chute being smooth, if desired the material will be expelled from such chute by centrifugal force and pass upwardly and outwardly over the annulus. If the bottom of said chute does consist of screened material, some of the water may, of course, be expelled at that point also. In any event, the water is accumulated in the

water box, whence it escapes at the waste discharge and the coal in the coal box, whence it escapes at the bottom.

I have shown the dish-shaped screen as placed in horizontal position. It could be, however, placed in any other desired position, since during its effective operation the force of gravity may be disregarded.

I claim:

1. A centrifugal drier comprising a screen, an outwardly and upwardly inclined discharge chute, a scraper adapted to travel over the surface of the screen and across the chute, means for rotating the screen and chute in unison and the scraper differentially, and means for supplying the material to the screen. 75

2. A centrifugal drier comprising an inclined screen and discharge chute the screen and chute portions being outwardly and upwardly inclined at different angles, a scraper adapted to travel over the surface of the screen and across the chute, means for rotating the screen and chute in unison and the scraper differentially and means for supplying the material to the screen. 85

3. A centrifugal drier comprising a dish-shaped screen and discharge chute, the screen and chute portions being outwardly and upwardly inclined the latter at a greater angle to the vertical than the screen surface, scrapers adapted to travel over the surface of the screen and across the chute, means for rotating the screen and chute in unison and the scraper differentially and means for supplying the material to the screen. 95

4. A centrifugal drier comprising a dish-shaped screen, a discharge chute outwardly and upwardly inclined with respect to the screen surface, a scraper adapted to travel over the surface of the screen and across the chute, means for rotating the screen and chute in unison and the scraper differentially and means for supplying the material to the screen. 105

5. A centrifugal drier comprising a dish-shaped screen, an outwardly and upwardly inclined discharge chute, a scraper adapted to travel over the surface of the screen and across the chute at substantially right angles to the line of travel of the material across the screen, means for rotating the screen and chute in unison and the scraper differentially and means for supplying the material to the screen. 115

6. A centrifugal drier comprising a dish-shaped screen and an outwardly and upwardly inclined radially disposed discharge chute, a scraper adapted to travel over the surface of the screen and across the chute substantially at right angles to the line of travel of the material over the screen, means for rotating the screen and chute in unison and the scraper differentially and means for supplying the material to the screen. 125

7. A centrifugal drier comprising a screen, an outwardly and upwardly inclined discharge chute, a scraper adapted to travel over the surface of the screen and across the chute, means for rotating the screen and chute in unison and the scraper differentially to move the scraper along the screen and means for supplying the material to the screen in front of the scraper and on the far side of the chute as the scraper travels around the screen.

8. A centrifugal drier comprising an inclined screen and a discharge chute outwardly and upwardly inclined at different angles, a scraper adapted to travel over the surface of the screen and across the chute, means for rotating the screen and chute in unison and the scraper differentially to move the scraper along the screen and means for supplying the material to the screen in front of the scraper and on the far side of the chute as the scraper travels around the screen.

9. A centrifugal drier comprising a dish-shaped screen and discharge chute, the latter outwardly and upwardly inclined at a greater angle to the vertical than the screen surface, scrapers adapted to travel over the surface of the screen and across the chute, means for rotating the screen and chute in unison and the scraper differentially to move the scraper along the screen and means for supplying the material to the screen in front of the scraper and on the far side of the chute as the scraper travels around the screen.

10. A centrifugal drier comprising a dish-shaped screen and discharge chute outwardly and upwardly inclined to the screen surface, a scraper adapted to travel over the surface of the screen and across the chute, means for rotating the screen and chute in unison and the scraper differentially to move the scraper along the screen and means for supplying the material to the screen on the far side of the chute, and in front of the scraper as it travels around the screen.

11. A centrifugal drier comprising a dish-shaped screen and outwardly and upwardly inclined discharge chute, a scraper adapted to travel over the surface of the screen and

across the chute at substantially right angles to the line of travel of the material across the screen, means for rotating the screen and chute in unison and the scraper differentially and means for supplying the material to the screen just beyond the chute in the direction of the travel of the scraper around the screen.

12. A centrifugal drier comprising a dish-shaped screen and outwardly and upwardly inclined discharge chute located in a substantially radial plane, a scraper adapted to travel over the surface of the screen and across the chute substantially at right angles to the line of travel of the material over the screen, means for rotating the screen and chute in unison and the scraper differentially and means for supplying the material to the screen just beyond the chute in the direction of the travel of the scraper around the screen.

13. A centrifugal drier comprising a dish-shaped screen with radial discharge chutes across its surface, a scraper adapted to travel around the dish-shaped surface and to pass over the discharge chutes, means for rotating the screen and the scraper differentially, water and material boxes surrounding the screen and means for driving the screen and scraper differentially and means for supplying the material to the screen.

14. A centrifugal drier comprising a dish-shaped screen with radial discharge chutes across its surface, a scraper adapted to travel around the dish-shaped surface and to pass over the discharge chutes, water and material boxes surrounding the screen, means for driving the screen and scraper differentially and means for supplying the material to the screen, said means adapted to discharge at one side of the chute in the direction of the travel of the scraper thereabout.

In testimony whereof, I affix my signature in the presence of two witnesses this 24th day of May, 1915.
